UNITED STATES PATENT OFFICE.

CHARLES HERBERT HOYT, OF NEW YORK, N. Y.

SPRING-MOTOR.

SPECIFICATION forming part of Letters Patent No. 724,009, dated March 31, 1903.

Application filed June 29, 1901. Serial No. 66,504. (No model.)

To all whom it may concern:

Be it known that I, CHARLES HERBERT HOYT, a citizen of the United States, residing in the borough of Manhattan, in the city and State 5 of New York, have invented a certain new and useful Improvement in Spring-Motors, of which the following is a specification.

My improvement is more especially applicable to that class of fans which serve by 10 means of a screw actuated by a spring wound up at intervals and employed to maintain a gentle current of air in the required general direction for a long period by the unwinding of the spring acting through multiplying 15 clock mechanism. I will describe it as thus applied.

I have devised a specially useful mode of combining several separately-supported sleeves each in its own independent bearings 20 and carrying springs, one on each sleeve, adapted to be brought into action singly or two or more at once at will, as will be set forth fully below, and pointed out in the claims.

The entire machine may be instantly applied 25 in a variety of positions for domestic, office, and general personal use. It is eminently adapted for use in sickness in warm weather.

The following is a description of what I 30 consider the best means of carrying out the invention.

The accompanying drawings form a part 35 of this specification.

Figure 1 is a rear elevation, partly in vertical section; and Fig. 2 is a side elevation, partly in vertical section.

Similar characters of reference indicate corresponding parts in both figures where they appear.

40 A is an upright rod of iron or steel, having a horizontal arm A' screw-threaded, as shown. The rod is received and held adjustably in a stand, (not shown,) which latter may be in all respects like the corresponding parts of 45 stands for supporting sheets of music for bands.

A is a jam-nut applied on the screw-threads.

B is the casing of my machine, provided 50 with base-pieces B', by which it may rest on a table when the stand is not being utilized, and also with an intermediate base-bar B², formed with a way B³ of dovetail cross-section,

adapted to receive a separately-formed screw-threaded socket M, which has a corresponding dovetail recess and is tapped to engage 55 with the aforesaid screw-threaded arm A'. This socket is capable of being easily attached and detached by sliding endwise on the dovetail ways B³. The socket can be applied on the screw-threaded arm by revolving it, and 60 when the screw-threads are thus well engaged it is strongly attached to the casing B by sliding on the way B³. This way is formed with a very slight taper, and the socket-piece M may be moved thereon until it wedges 65 tightly, after which the socket and casing together may be set so as to present the casing B upright or inclined at any desired angle, and by turning the jam-nut A² to induce pressure against the socket-piece the machine 70 is firmly held at the required angle. This permits it to send the gentle current of air either level or inclined downward or upward upon a table or sick-bed.

I employ an upright shaft G with bevel-gear 75 at each end through which to communicate motion from bevel-gear H' in clock mechanism H in the casing B to a small bevel gear-wheel D³ on the shaft D of a screw-fan. The series of springs for impelling the multiplying 80 or clock mechanism H and the several separately-supported sleeves, one for each spring, and the provisions for using the several sleeves in winding the springs and disconnecting when not required constitute the main 85 subject of the invention.

I make the mechanism run a long time by means of several springs, each attached to a metallic sleeve, each of which, with a spring attached, carries a large wheel and is adjusted on the main shaft 1 to run freely thereon. A ratchet-wheel 2, one for each sleeve, is firmly keyed or otherwise fixed to the shaft 1 and engaged with a pawl 3, attached to the adjacent sleeve 4, and a separate friction-brake 5, working on the sufficiently large friction-wheel constituting a part of each sleeve, withholds the power of each spring at will. When any spring 7 is thus conditioned, the shaft 1 turns without its aid. On releasing any brake 5 the dynamic power of the corresponding spring 7 is at once communicated through the pawl 3 and ratchet 2, and thus to the main shaft 1, and contributes its

force to turn the shaft and drive the clock mechanism II. By this combination thus arranged each spring exerts its power independently, yet is applied and taken off at will. The power of two or more or of all can be applied at the same time to impel the main shaft by simply taking off two or more brakes at once. The several springs 7 are independently wound by releasing each brake and turning it by means of worm-gears, one worm 8 connected at will with each wheel 4. Each worm may be held in gear or dropped out of gear, so as to be idle, by turning a piece 9. The projecting end of each worm-shaft 8 is squared and receives in its turn a proper winding-key, which may be a crank. (See Fig. 1.) Such is easily transferred from one worm-shaft to another, as required in winding operations. The partitions B³ serve as independent bearings for the several sleeves 4, which greatly relieve the constantly-running shaft 1 from the lateral pressure in different directions, to which it would be otherwise subjected.

25 I attach importance to the brake as means for holding the several springs out of use for the reason, among others, that they can be applied at any time. It is often desirable to vary the force of the blowing or other work, and my brakes allow an additional spring to be applied or when several are working to have one or more arrested and allow the remainder to continue with little trouble and without stopping the machine. The brakes also allow the force to be varied by gentle changes.

Modifications may be made by any good mechanic without departing from the principle or sacrificing the advantages of the invention.

30 The width and the angularity of the position of the several screw-blades R S T may be varied with the effect, among others, to retard or accelerate the uncoiling of the several

45 springs. I have shown an efficient winding-key W, adapted to be operated by one hand applied on the squared end of a worm-shaft 8 for winding up one spring. All these parts can be varied. I have in my experiments used multiplying gear analogous to clock mechanism mounted in a stoutly-braced metal frame in the casing B. I have used springs 7, each corresponding to a clock-spring, but larger than those used in ordinary clocks.

50 Instead of the worms 8 for effecting the winding of the several springs that operation 55 may be effected by spur-gear in the obvious manner.

I claim as my invention—

1. A motor comprising a series of springs supported continuously and fairly in fixed 60 bearings, a brake B³ for each spring for liberating and arresting at will, and a pawl for holding each spring idle when desired, and a pawl for connecting each spring to the main shaft as required, combined and arranged for joint 65 operation substantially as herein specified.

2. A motor composed of a series of springs mounted on separate sleeves capable of turning separately and supported independently in fixed bearings, means for holding each 70 spring idle when desired, and a pawl for connecting each spring to the main shaft as required, and winding means S, one for each sleeve, and the movable pieces 9 for throwing the winding means into and out of engagement at will, all combined and arranged for joint operation substantially as herein specified.

In testimony that I claim the invention above set forth I affix my signature in presence of two witnesses.

CHARLES HERBERT HOYT.
